(57) **CLAIM**

The ornamental design for a spa jet, as shown and described.

DESCRIPTION

FIG. 1 is a perspective view of a spa jet showing our new design;

FIG. 2 is a side elevational view thereof;

FIG. 3 is an opposing side elevational view thereof;

FIG. 4 is a top plan view thereof;

FIG. 5 is a bottom plan view thereof;

FIG. 6 is a rear elevational view thereof;

FIG. 7 is a front elevational view thereof;

FIG. 8 is a perspective view of a second embodiment of a spa jet showing our new design;

FIG. 9 is a side elevational view of the spa jet shown in FIG. 8;

FIG. 10 is an opposing side elevational view of the spa jet shown in FIG. 8;

FIG. 11 is a top plan view of the spa jet shown in FIG. 8;

FIG. 12 is a bottom plan view of the spa jet shown in FIG. 8;

FIG. 13 is a rear elevational view of the spa jet shown in FIG. 8; and,

FIG. 14 is a front elevational view of the spa jet shown in FIG. 8.

The broken line portions of the disclosure are for illustrative purposes only and form no part of the claimed designs.
